UNITED STATES PATENT OFFICE.

EARL A. THISSELL, OF LOWELL, MASSACHUSETTS.

WEFT-REPLENISHING MECHANISM FOR LOOMS.

SPECIFICATION forming part of Letters Patent No. 733,884, dated July 14, 1903.

Application filed April 7, 1902. Serial No. 101,620. (No model.)

To all whom it may concern:

Be it known that I, EARL A. THISSELL, a citizen of the United States, residing in Lowell, in the county of Middlesex and Commonwealth of Massachusetts, have invented a certain new and useful Improvement in Weft-Replenishing Mechanisms for Looms, of which the following is a specification.

This invention relates to weft-replenishing mechanisms for looms.

In another application, Serial No. 61,351, filed May 22, 1901, and now pending I have shown, in connection with a rotary shuttle-changer carried by the lay and forming with a binder a shuttle-box, a stationary magazine from which a shuttle is allowed to fall as required, guides between the magazine and shuttle-changer to receive the falling shuttle, and means for crowding a shuttle after it leaves the magazine through said guide into the shuttle-changer.

In the present invention I have so arranged the magazine that its lower or discharging end swings with the lay and is always over the shuttle-changer and allows the lowermost shuttle in the magazine to fall by its own weight directly into the shuttle-changer whenever the uppermost compartment of said shuttle-changer passes in under said magazine, and I dispense with all guides between said magazine and said shuttle-changer and with all positive means of crowding said shuttle into said changer.

By the construction herein set forth I am also enabled to dispense with any contrivance aside from the shuttle-changer for retaining shuttles in the magazine, the stack of shuttles in the magazine resting upon and being prevented from escaping by the shuttle in the uppermost compartment of the shuttle-changer. I have also provided means of supporting the magazine in such a manner that while its lower end moves with the lay the movement of the top of said magazine is so slight as not to render it at all difficult to fill the magazine while the lay is in motion. I have also shown a "relief" designed to prevent the operation of the shuttle-changing mechanisms except when the binder is thrown forward by a shuttle entering the box.

In the accompanying drawings on six sheets, Figure 1 is a side elevation of so much of a

loom provided with my improvement as is necessary to the understanding of the same; Fig. 2, a front elevation of the same; Fig. 3, a vertical section from front to rear of the magazine and shuttle-changer on the line 3-3 in Fig. 4, showing also shuttles in end elevation in said magazine and shuttle-changer; Fig. 3^a, an outer side elevation of the shuttle-changer and its impelling-pawl, pawl-lever, operating-rod, the binder, picker-stick, and picker; Fig. 3^b, a rear elevation of the shuttle-changer, pawl-lever, and operating rod or link; Fig. 3^c, a section of the pawl-lever and pawl on the line 3^c-3^c in Fig. 3^a, said section being on a plane at right angles to the pivot of the pawl; Fig. 4, a front elevation of the empty magazine and shuttle-box; Fig. 4^a, a plan of the magazine containing shuttles and of the upper supporting means of said magazine; Fig. 5, a side elevation of the shuttle-changing lever and its operating-cam and the clutch which connects the cam-shaft and cam; Fig. 6, a side elevation of said cam and clutch, the position of the cam being the reverse of that shown in Fig. 5; Fig. 7, a vertical transverse section on the line 7-7 in Fig. 6; Fig. 8, a horizontal transverse section on the line 8-8 in Fig. 6.

The frame A, arch a, lay B, lay-beam b, crank-shaft C, having a crank c connected by a link c' to the lay B, the picker-stick E, the picking-strap e, the binder-spring d, and the shuttle-box port or mouth d' are of any usual construction and operation and are used in connection with the usual harness, let-off and filling-stop motions, and with the cloth-take-up-devices commonly used in broad looms for weaving plain cloth or ginghams.

The magazine F, Figs. 1, 2, 3, 4, and 4^a, is a case having a back f, which to save weight may be of wood, and ends f' f'', the front edges of which are turned toward each other in such a manner that the ends of the case will loosely hold shuttles G, of ordinary construction, stacked therein from lateral or endwise movement, the filled shuttles being piled on each other in the magazine with the bottoms of the shuttles in front and the delivery sides of the shuttles on top. The lower end of the magazine is hinged to the lay and partakes of the motion of said lay. The lower end of the magazine has rigidly secured to its sides,

Figs. 1 to 4, knuckle-plates $f^3 f^4$, through the lower ends $f^5 f^6$ of which pintles $f^7 f^8$ are driven horizontally into stands $f^9 f^{10}$, which may be integral with or secured, as by bolts, 5 to the stands $i i'$, in which the shaft I of the shuttle-changer M is supported, as hereinafter described, said last-named stands being secured to the back of the lay-beam b and the knuckle-plates and stands $f^9 f^{10}$ forming 10 hinges.

To the back of the magazine F, near the top of the same, Figs. 1, 2, 3, 4, and 4^a, is secured another knuckle-plate f^{11} , which is connected by a link f^{12} to a bracket or stand f^{13} , 15 rigidly secured on the arch a, said link being pivoted to said knuckle-plates at $f^{14} f^{15}$ in a usual and obvious manner. When the lay is farthest from the breast-beam a', the link stands at an angle of about forty-five degrees 20 to the vertical; but as the lay swings forward the upper end of the link is drawn forward and downward slightly, but without any considerable movement in a forward direction, the upper end of the link passing through an 25 arc of about forty degrees. It will be understood that I do not intend to limit myself to the exact positions of the link herein given or to the amount of its movement. By this means of supporting the magazine it is possible 30 to place shuttles in the top of the magazine while the loom is running without special skill or attention and without previous practice. The shuttles pass through the magazine and are discharged therefrom by their 35 own gravity solely. Any rotary shuttle-changer which can be supplied by shuttles falling singly into the compartments thereof may be used.

I have shown the shuttle-changer M, described in said previous application, the same 40 consisting of a hub m' and two or more, preferably four, wings m^2 . The faces m^3 of the hub are equal in number to the wings and are plain surfaces arranged parallel with the 45 axis of the hub and are adapted to support the back of the shuttle. The wings m^2 are so arranged on the hub m' (which is square in cross-section) at the corners of the hub as to form between each wing and the next a 50 shuttle-receiving channel, the wing in advance having a surface m^6 at right angles to the adjacent face m^8 of the hub, which furnishes a bearing for the bottom of the shuttle, and the top of the shuttle on both sides of 55 its bobbin-chamber resting against the surface m^4 and the outer portion of the following wing.

The shuttle-changer M is free to turn upon a shaft I, which is supported in the stands $i i'$, 60 above mentioned. The pawl-lever P turns on the shaft I at the inner end of the shuttle-changer M and is concave on its upper side to avoid contact with the lower rear corner or edge of the shuttle and is convex on its lower 65 edge to support ears $p' p^2$, between which the pawl p is pivoted, the pivot p^3 being arranged at right angles to the shaft I. The free end

or head p^4 of the pawl p engages the surface m^6 and is preferably shaped to fit in the angle made by this surface m^6 and the adjacent 70 face m^3 of the hub of shuttle-changer. The pawl is so pivoted that its weight will naturally throw its free end into engagement with the shuttle-changer; but for greater safety I use a spiral spring p^5 , which throws said free 75 end toward said changer and yields to allow said pawl to ride over the wing in the return movement of said pawl-lever. The free end of the pawl-lever P is connected by the rod or link Q to a lever R, pivoted at r back of 80 and below the crank-shaft C, the weight of said lever R when unsupported being sufficient to swing said pawl-lever backward to engage a new notch in the shuttle-changer.

The front end of the lever R is provided 85 with a lateral projection r' , normally resting on a shoulder t on the lower arm t' of the lever T, fast on the stop-motion rock-shaft U, the upper arm t^2 of said lever T extending upward and engaging the stop-motion slide V. 90 The stop-motion fork v is fulcrumed on the slide V and tilted by the filling-thread in the usual manner and has on its front end the usual hook v' , which in the absence of the filling engages the hammer w of the lever W, 95 the latter being oscillated at every other forward swing of the lay by a wiper x, fast on the cam-shaft X, raising the rear end of said lever W in the usual manner, so that in the absence of the filling the shaft U is rocked 100 and draws the shoulder t out from under the projection r' and allows the lever R to fall and engage a new notch of the shuttle-changer. The further revolution of the cam-shaft X causes another cam Y to lift the lever R and turn the shuttle-changer an angular distance represented by a notch or ratchet-tooth, causing the shuttle in the shuttle-box—that is, the shuttle which is between the binder and the hub of the shuttle-changer— 110 to be crowded downward out of the box by the wing m^2 immediately above it, while the next following wing puts in a new shuttle.

One of the wings of the shuttle-changer forms the top of the shuttle-box, and a face 115 m^3 of the hub of said changer forms the back of the shuttle-box, the front of the shuttle-box being formed by the binder J like that shown in said previous application and differing from binders in common use only in 120 being provided on its upper edge with a finger j, curved upward and backward, to prevent the shuttle being thrown by the shuttle-changer over the top of the binder, and in being provided at its lower edge with a back- 125 wardly-extending horizontal ledge j^3 , which with the surface m^6 , above referred to, form the shuttle-race or bottom of the shuttle-box. The binder is pivoted on the binder-stud j^4 , is directed horizontally by the binder-guide j^5 , and is closed by the binder-spring d, all in 130 the usual manner. When a shuttle is entirely out of the shuttle-box, the changer cannot be rotated without causing one of the

wings m^2 to strike on the binder, thereby breaking the wing or the binder or some connected part, and when a shuttle is partly out of and partly in the box such shuttle would be broken by the rotation of the changer.

To prevent the rotation of the changer in either case, I connect the cam Y to the cam-shaft X in such a manner that while under ordinary resistance said cam will turn with said shaft to raise the lever R, yet if the rotation of the shuttle-changer is obstructed by the binder or by a partially-boxed shuttle said cam Y will slip on said shaft and not raise said lever, and therefore not turn the shuttle-changer. Said cam Y is loose on the shaft X and is provided with a flange y. (See Figs. 5 to 8.)

A collar Z is fast on the cam-shaft X and has pivoted thereto or to a projection z, with which said collar is provided, an arm z', adapted to swing at right angles to said cam-shaft, and a spring z² is arranged to throw the free end z³ of said arm outward against the inner surface of said flange y and to exert sufficient friction on a part of said flange normally to rotate said cam Y with said shaft X, said outer end z³ extending laterally within said flange, and said spring z² being represented as a helical wire spring z³, one end of which bears against the projection z, while the other end is fastened to the spindle z⁴ of the arm z', which spindle turns freely in said projection z and is surrounded by said spring outside of said projection, the tendency of said spring to unwind holding the end z³ of said arm against said flange.

The flange y of the cam Y is represented as having two parts y' y², each concentric with the shaft X, the part y' having a less radius than the part y², and along these parts the outer end z³ of the arm z' slides without difficulty. Two other parts y³ y⁴ are represented as about parallel with each other and as connecting the ends of the parts y' y². The essential feature in the shape of said flange, however, is the angle y⁵, where the end z³ of the arm z runs from the part y² onto the part y³ and suddenly meets greater resistance to its progress by the rapidly-decreasing radius of the flange. At this angle the friction between the flange and arm is so great that the cam will revolve with the shaft against ordinary resistance; but when the raising of the lever R is abnormally obstructed by reason of either of the accidents above referred to the arm will slip past the angle y⁵ and the cam will yield at each revolution of the cam-shaft until the obstruction is removed.

I claim as my invention—

1. The combination of a lay, a shuttle-changer rotary on said lay, a stud secured vertically to said lay, a binder swinging on said

stud, said changer and binder together forming a shuttle-box, and a magazine adapted to hold a stack of shuttles and attached at its lower end to said lay and adapted to discharge directly into said changer.

2. The combination of a lay, a rotary shuttle-changer carried thereby, a magazine, pivoted at its lower end to said lay and adapted to hold a stack of shuttles and to discharge said shuttles singly into said changer as said changer rotates, and a stationary support, to which said magazine is connected above the lower end to reduce the movement of the upper end of said magazine and to facilitate the placing of shuttles therein.

3. The combination of a lay, a rotary shuttle-changer and a binder both carried by said lay, said changer and binder together forming a shuttle-box, a magazine, pivoted at its lower end to said lay and adapted to hold a stack of shuttles and to discharge said shuttles singly into said changer as said changer rotates, and a stationary support to which said magazine is connected at its upper end, to reduce the movement of said upper end and to facilitate the placing of shuttles in said magazine.

4. The combination of a loom-frame, a lay, a rotary shuttle-changer carried by said lay, a magazine pivoted at its lower end to said lay and arranged to discharge immediately into said changer, and a link jointed to and connecting said frame and said magazine above the lower end of said magazine.

5. The combination of a loom-frame, a lay, a rotary shuttle-changer and a binder carried by said lay, said changer and binder together forming a shuttle-box, a magazine pivoted at its lower end to said lay and arranged to discharge immediately into said changer, and a link jointed to and connecting said frame and said magazine above the lower end of said magazine.

6. The combination of a rotary shuttle-changer, provided with a ratchet, a pawl, a rod operating said pawl, a cam-shaft and means for actuating said rod by the rotation of said shaft, said means comprising a cam normally rotary with said shaft but adapted to yield to an abnormal resistance.

7. The combination of a cam-shaft, a cam, normally rotary with said shaft and yieldingly connected therewith, a lever raised by said cam, a rotary shuttle-changer, means for rotating said changer by the rising of said lever, and a latch, normally engaging said lever and holding the same in a raised position.

In testimony whereof I have affixed my signature in presence of two witnesses.

EARL A. THISSELL.

Witnesses:

ALBERT M. MOORE,
JOHN F. FOSS.
